UNITED STATES PATENT OFFICE.

JOHN WILLIAM WULF, OF SAN JUAN, PORTO RICO.

FUSE-PLUG.

1,373,696.

Specification of Letters Patent.

Patented Apr. 5, 1921.

Application filed July 7, 1919. Serial No. 308,983.

To all whom it may concern:

Be it known that I, JOHN WILLIAM WULF, a citizen of the United States, and a resident of San Juan, Porto Rico, have invented a new and useful Improved Fuse-Plug, of which the following is a full, clear, and exact description:

This invention relates to a new and improved fuse plug, and has reference more particularly to a device of this kind, which comprises a body having spaced terminals and a fuse connecting the terminals, the body providing a receptacle for a spare fuse, which is normally separated from the live fuse connecting the terminals.

An object of the invention is to provide a simple and durable fuse plug for use with electric circuits of different kinds, which can be inexpensively produced, and in which the fuse is readily renewable.

A further object of the invention is to provide a fuse plug in which soldered connections are avoided, in which a substantial length of spare fuse is available at all times, for replacing the live fuse should the same be burned out, and in which the spare fuse is protected against injury which might be occasioned incident to the burning out of the live fuse.

A still further object of the invention is to provide a fuse plug in which the fuse is easily visible at all times, which has a self-contained spare fuse for replacing the burned out fuse, and which provides means for guarding the spare fuse against injury, while leaving the same readily available for use.

The invention consists in the construction and combination of parts, to be more fully described hereinafter and particularly set forth in the claims.

Reference is to be had to the accompanying drawings forming a part of this specification, in which similar characters of reference indicate corresponding parts in all the views, and in which—

Figure 1 is a longitudinal section of an embodiment of my invention;

Fig. 2 is a plan view showing the covering cap in cross section;

Fig. 3 is a partial longitudinal section at right angles to the section of Fig. 1; and

Fig. 4 is a detail view of a terminal employed with the device.

Before proceeding to a more detailed ex-

planation of my invention, it should be understood that the fuse plug can be used in connection with electric circuits of different kinds. It may be fashioned from any suitable material customarily employed, and may be produced in different sizes and shapes. Certain of the details of construction form no part of the invention and may be varied in accordance with necessity or preference, without departing from the spirit of the invention.

Referring more particularly to the drawings, I provide a fuse body 10, of porcelain or other di-electric material, and having the lower part 11 threaded to receive a suitable, correspondingly threaded metal ferrule 12, by means of which the plug is screwed into a socket adapted to receive it. At the upper end, the plug has a laterally extended head 13, which is threaded to receive a correspondingly threaded flange 14 of an annular cap 15 of sheet metal or the like. The annular cap seats upon the top of the fuse and holds in position a glass or mica sheet 16 extending over the open-ended chamber 17 formed within the body, so that the interior of the plug can be inspected through the transparent sheet 16.

The lower end 18 of the body is preferably tapered. It has a longitudinal bore 19 opening into the chamber 17. A cylindrical terminal 20 is received in the bore 19 and has a flat head 21 seating against the lower end of the body and adapted to engage a suitable contact of the electric circuit with which the fuse plug is used. The terminal 20 is provided with a substantially central, threaded bore 20^a, and has two tapered, spaced fingers 20^b at the end opposite the head 21. A binding or cap screw 26 is received in the bore 20^a, and serves to secure the wire 28 to the terminal. The bottom of the chamber 17 is provided with a pair of opposite grooves 19^a adapted to receive the fingers 20^b when the latter are spread apart and turned outwardly as the screw 26 is forced home. In this way the terminal 20 is prevented from turning when the fuse plug is screwed into the socket. At its upper end the chamber 17 has a lateral extension or recess 22 from which projects a metal plate 23. A downwardly extending opening 24 is formed in the body and extends from the recess to the outside of the body, just under the head 13. The plate 23

has an extension 25 disposed in the opening 24 and contacting with the metal ferrule 12, as is shown in Fig. 3. The terminal 20 and the plate terminal 23 are respectively provided with screws 26 and 27 by means of which a length of fusible wire 28, constituting the fuse proper, is secured to the terminals. It will be seen that the circuit includes the terminal 20, the fuse wire 28, the 10 terminal 23, and the ferrule 12.

An annular channel 29 is formed in the upper face of the body, surrounding the chamber 17 and preferably concentric therewith. The channel 29 communicates with 15 the recess 22. It constitutes a chamber to receive a length of spare fuse 30, which extends from and beyond the terminal 23. It will be seen that the mica or other plate 16 and the annular flange of the cap 15 extend over and close the channel or chamber 29, so that when the plug is in use the spare fuse is protected against injury should the fuse 28 blow out. It is readily made 20 available for use, however, by simply unscrewing the cap.

Having thus described my invention, I claim as new and desire to secure by Letters Patent:

1. A fuse plug, comprising a body, spaced 30 terminals carried thereby, and a fuse connecting said terminals, said body having a part adapted for the reception of a spare fuse, normally separated from said fuse connecting said terminals, said spare fuse being connected to one of said terminals and branching therefrom for disposition in said receiving part.

2. A fuse plug, comprising a body having spaced terminals, and a fuse connecting said 40 terminals, said fuse having a spare length extending beyond one of said terminals, said body having a chamber in its outer end adapted for the reception of said spare length.

3. A fuse plug, comprising a body having spaced terminals, and a fuse connecting said terminals, said fuse having a spare length connected to and extending beyond one of said terminals, said body having an annular 50 groove in its outer face forming a chamber adapted for the reception of said spare

length and having an opening near said one terminal.

4. A fuse plug, comprising a body having spaced terminals, a fuse connecting said terminals, said fuse having a spare length extending beyond one of said terminals, said body having an annular chamber in its outer end adapted for the reception of said spare length and having an opening near said one 55 terminal, and means for normally covering said chamber to protect said spare length of fuse therein.

5. A fuse plug, comprising a hollow body, terminals extending into said hollow body, a cover for said hollow body, and a fuse connecting said terminals, said body having an annular chamber in one end adapted for the reception of a spare fuse, and normally covered and closed by said cover. 60

6. A fuse plug, comprising a body having a threaded part and a chamber therein opening at one end of said body, terminals extending into said chamber and adapted to be connected by a fuse, a transparent plate 75 over the open end of said chamber, a cap removably fitted upon said body and holding said plate in position, said body having a second chamber surrounding said first chamber and opening near one of said terminals, said second chamber being adapted for the reception of spare fuse and being normally covered by said cap. 80

7. A fuse plug, comprising a body having a chamber opening at one end of 85 said body, said body having at the upper end thereof a second chamber surrounding said first chamber, said first chamber having a lateral recess extending to said second chamber, a terminal arranged in said recess and extending into the said first chamber, a second terminal at the opposite end of said body and extending into said first chamber, a ferrule encompassing said body, an electrical connection between said 90 first terminal and said ferrule, said second chamber being adapted for the reception of a spare fuse, and a cover over the open end of said body and closing both of said chambers.

JOHN WILLIAM WULF.
